I. C. Koehne

UNITED STATES PATENT OFFICE.

IRA C. KOEHNE, OF DAYTON, OHIO.

DESIGN FOR A BASE-FRAME FOR SCALES.

SPECIFICATION forming part of Design No. 31,922, dated December 5, 1899.

Application filed October 30, 1899. Serial No. 735,315. Term of patent 31 years.

To all whom it may concern:

Be it known that I, IRA C. KOEHNE, a citizen of the United States, residing in Dayton, in the county of Montgomery and State of Ohio, have produced a new and original Design for a Base-Frame for Scales, of which the following is a specification, reference being had to the accompanying drawings, forming part thereof, in which like numerals refer to like parts.

In the drawings, Figure 1 represents a plan view of a base-frame for a scale embodying my invention and design, and Fig. 2 is a sectional elevation view thereof on line X X of Fig. 1.

The leading or essential feature of my de-

sign for a base-frame for a scale consists of a circular vertically-extending member having an opening through its top.

In said drawings, 10 represents said circular vertically-extending member, and 11 represents said opening through the top thereof.

What I claim is—

The design for a base-frame for a scale, substantially as shown and described.

In witness whereof I have hereunto set my hand this 30th day of September, 1899.

IRA C. KOEHNE.

Witnesses:

H. M. WALSH,
L. D. HELLER.
